CUTTER SALVAGE MACHINE

Floyd J. Aker, Newark, N. J., assignor to Eastern
Cutter Salvage Corporation, a corporation of
New Jersey

Application January 18, 1932, Serial No. 587,224

3 Claims. (Cl. 51—95)

This invention relates to a machine for grinding cutting tools such as end mills, side mills, angle cutters, counter bores and the like and relates more particularly to a machine for practicing a method of grinding and equalizing the space between the teeth of cutters as set forth in my copending application Serial No. 587,223 filed January 18, 1932 for Method of grinding cutters.

10 The operation of salvaging a cutter involves not only the removal of material to shape new teeth but in shaping the teeth so that the grinding operation serves to equalize or accurately space the teeth and furthermore the grinding 15 must be accomplished at relatively high speed and at low cost.

Machines have heretofore been used to salvage cutters and such machines were constructed along the lines of machines employed for a 20 variety of grinding operations. Such machines as commonly constructed could be used to re-grind a cutter but inasmuch as these machines were made to meet the requirements of other grinding operations they did not have an arrangement of cooperating elements capable of 25 meeting the demands encountered when an efficient salvaging operation was required.

If a salvaging operation is to be profitable it must be accomplished in such manner that the 30 cost thereof does not too closely approach the selling price of a new tool.

Cutting tools being made of high speed steel are extremely hard and are ordinarily difficult to grind and when ground on the usual or standard type of grinders the operation is unsatisfactory for the following reasons:

First, the machines are so constructed that relatively light cuts are taken usually of a maximum depth of .002 to .003 of an inch since the 40 construction of the machine is such that the movement of the work moved for a grinding operation, is positive and not under the control of the operator. By reason of this construction a heavy cut is prohibitive in that it would result 45 in over-heating of the tool causing it to lose its temper or in scorching the surface.

Second, the position of the operator with relation to the work is such that he has no opportunity of observing the degree of cut being taken 50 and must depend upon the machine.

Third, it has been found that when grinding cutters to obtain the best result it is essential that the operator practice the grinding operation in such manner that he is able not only to 55 observe the cut being taken but is able to

"feel" or "sense" the degree of cut which is not possible with machines as heretofore employed.

Fourth, although it is well recognized that it is common practice to provide slip clutches for various mechanisms it is important that the 60 driven grinding wheel slips when too heavy a cut is taken and that the operator be able, when too heavy a cut is taken, to easily and quickly adjust the relation of the wheel and cutter which was not possible with machines as heretofore 65 constructed.

An object of the present invention is therefore, to provide a grinding machine which, when in the hands of an operator will have the necessary 70 flexibility to permit him, without the exercise of any unusual skill, to practice a method of economically and expeditiously grinding cutters.

Another object of the invention is to provide a cutter grinding machine in which the powerful grinding force of a rotating abrasive element 75 may be employed in much the same manner as a hand carving tool except that in the present case the operator need only control the work being performed.

Another object of the invention is to provide 80 an efficient grinding device wherein speed and accuracy are attainable in the absence of skilled labor or costly and complicated mechanisms.

Other objects and advantages of the invention will be readily understood by reference to the 85 accompanying drawings in which

Fig. 1 is a front elevational view of a machine embodying the present invention showing a cutter supporting mechanism in vertical cross section;

Fig. 2 is a side elevational view of the machine shown in Fig. 1;

Fig. 3 is a horizontal sectional view taken on lines III—III in Fig. 1;

Fig. 4 is a view of the cutter and its support 95 taken on lines IV—IV in Fig. 2;

Fig. 5 is a fragmentary view showing a portion of a worn cutter with a grinding wheel for making the initial slots;

Fig. 6 is a view similar to Fig. 5 but showing 100 a grinding wheel for performing the roughing cut on the teeth;

Fig. 7 is another fragmentary view similar to Fig. 6 but showing a wheel for finishing the teeth.

A machine constructed in accordance with the present invention may comprise a supporting frame 10 having a suitable foot piece 11 and an upper bearing bracket 12. The frame 10 is provided with a carrier 13 including a threaded 110

extension 14 extending through a suitable vertical slot 15 in the frame 10. A vertical screw 16 extends through the threaded portion of extension 14 and the lower end of the screw is provided with a bearing pin 17 rotatable in a boss 18, the upper end of the screw extends through a bearing 19 integral with frame 10 and is provided with a bevel gear 21.

The bevel gear is disposed in mesh with a bevel gear 22 secured to one end of a horizontal shaft 23. The shaft 23 is suitably journaled in the frame 10 and its opposite end is provided with a hand wheel 24. A rotation of the hand wheel causes an actuation of the screw 16 to raise or lower the carrier 13.

The carrier 13 is provided with a slideable carriage 25 movable on guides 26, 26 and is provided with a nut 27 on an extension 28. A screw 29 passes through the nut and one end of the screw is journaled at 31 in the carriage 13. The opposite end of the screw is rotatable in a bearing 32 and is provided with a hand crank 33.

A manipulation of the crank 33 serves to move the carriage 25 forward and backward in relation to the frame 10. The carriage 25 is provided with a U-shaped support member 34 having a bolt 35 extending through its base portion 36. The head of the bolt is disposed in a slot 37 in the carriage 25 so that the member 34 may be moved relative to the carriage and held in position by tightening the bolt 35. The upper or exposed end of the bolt 35 is provided with a nut 38. Thus when the nut 38 is loosened the support member may be adjusted and when the nut is tightened the support member may be fixed in a given position with relation to the carriage 25. It will be evident that by reason of this construction the support member can be rotated in a horizontal plane and held in any position.

The U-shaped member 34 includes arms 39 and 41 having split bearings 42 and 43 respectively to receive a rod or arbor 44. The bearings 42 and 43 are adjustable by means of suitable screws 45 so that the arbor may readily be slid into position and clamped. This arbor serves as a guide to direct a cutter or other work part to be ground through a rectilinear path. If desirable a cutter or work part to be ground may be mounted directly on the arbor and the arbor may be adjusted in the bearings 42 and 43 and the bearings clamped sufficiently to hold the arbor but permit it to be slid forward and backward to carry the work part or the cutter may be slideable directly on the arbor. It is preferable, however, to mount a work part as for example a cutter 46 on a sleeve 47 as shown in the drawings.

As shown more clearly in Fig. 4 the sleeve 47 may be of sufficient length to accommodate cutters of various lengths and spacer members 47' may be employed to clamp the cutter between a shoulder 48' and a nut 50 which threadededly engages one end of the sleeve.

A guide piece or finger 51' is provided to engage a tooth of the cutter to hold it against rotation during a grinding operation and as will be noted from the drawings the position of the grinding wheel with respect to the axis of rotation of the cutter is such that as the cutter is forced beneath the grinding wheel the tendency of the cutter is to rotate so as to firmly engage the finger with a tooth.

The finger 51' is adjustably mounted on an arm 52' by means of a tap bolt which is disposed

in a slot 53' in the arm 52'. When the bolt is loosened the finger may be moved in a straight line within the limits of the slot and may also be moved through an arcuate path about the bolt which serves as a pivot.

The arm 52' is secured to the base 36 of the support 34 by a tap bolt 54' which may be manipulated to permit an adjustment of the arm and the finger 51' mounted thereon. By reason of the adjustability of the finger and its support, the finger may be set to angles of the teeth of cutters of various types.

When the finger 51' is adjusted the cutter may be moved back and forth by means of a hand piece 55'. The cutter is allowed sufficient movement along the arbor to permit it to clear a grinding wheel 52 and the finger 55' at which time the operator rotates the cutter to bring another tooth in position to be ground and another tooth is engaged by the finger.

Suitably positioned above the work support is a shaft 49 having a head 51 of any suitable type to hold the grinding wheel 52. It has been found in practice that the grinding operation causes excessive strain which ordinarily results in mis-alignment of the shaft 49 or rapid wear resulting in chattering.

In the construction shown this disadvantage is overcome by providing a tapered bearing 53 (see Fig. 3) and a hardened center bearing 54 for the shaft 49 which latter bearing is engaged by a hardened center point 55 disposed in an adjustable support 56. The support 56 is provided with a split collar 57 clamped to a support rod 57' secured to the bracket 12. The shaft 49 is provided with a pulley 58 driven by a belt 59 from any suitable source of power (not shown). By reason of the construction including the tapered bearing 53 and center bearing 54 rotatable about the center 55 it is possible to run the grinding wheel to take heavy cuts without the rapid wear which would otherwise occur. The tapered bearing 53 which is a bushing is provided with a take up nut 61 so that the bushing may be adjusted to maintain its running fit when worn. A pair of lock nuts 62 on threaded portion 63 of the shaft 49 serve to secure the shaft to the bushing 53 for rotation therewith.

The present machine is useful for the convenient grinding of cutters by following any chosen method but is especially advantageous when practicing the method set forth in the above mentioned copending application. When practicing this method a cutter having any number of teeth may be mounted on the arbor 44. The teeth of cutter to be reformed may have been worn down as shown at 60' in Fig. 5 leaving slots or notches 61'. The sides 62' or faces of the worn teeth are taken as the starting surface for the space equalizing process during grinding.

The first grinding operation is preferably performed with a gashing or narrow saucer wheel 63' which is used to form slots 64 to a depth selected for the equalizing operation. The finger 51' is set to engage a tooth which is spaced from the tooth being ground by a plurality of teeth. On a ten tooth cutter it has been found desirable to set the finger three spaces or teeth from the face in operative relation to the grinding wheel. The finger is then adjusted to engage a tooth and the hand wheel 24 and hand crank 33 are manipulated to bring the tooth to be ground in such relation to the grinding wheel that a relatively heavy cut will be taken when the cutter is moved along the arbor.

5 The grinding wheel rotates in the direction of the arrow X or in a counter-clockwise direction. The wheel is coarse grained and of a diameter of about eight inches and about one quarter of an inch wide. It will be noted that the grinding wheel 52 is positioned off center with respect to the axis of rotation of the cutter so that when the wheel engages the cutter for a grinding operation it serves to hold the tooth in 10 firm engagement with the finger.

10 The pulley 58 on the shaft 49 is preferably $\frac{3}{4}$ inches in diameter and the belt 59 is of leather and is preferably 2 inches wide. The shaft is rotated at a speed of about 1750 to 2300 R. P. M. 15 By reason of the relation of the pulley and belt friction ratio the operator is prevented from taking too deep a cut since if the cut is too heavy the belt will slip.

15 Having set the cutter for a selected cut it is drawn toward the operator who is positioned in front of the machine and as indicated in Fig. 2 has a line of sight along the tooth being ground. As he pulls the cutter toward him he is able to observe the grinding operation and at the same 20 time "feel" the character of the cut.

20 When the face of the initial tooth has been ground he moves the cutter to a rear position so that the teeth clear the wheel and finger and rotates the cutter in the direction of the arrow Y or toward the finger and engages the next tooth with the finger so that the cutter is in position to have another tooth face ground adjacent to the first ground tooth. This operation is repeated until a ground tooth reaches the finger. When 25 this occurs the operator, by reason of the present construction, may start to cut and will be able to "feel" and observe that the cut is too deep since the cut on the tooth which would engage the wheel will be twice as heavy as the previous 30 cut. The operator then moves the cutter by manipulating hand crank 33 to change the space relation between the finger and the wheel bringing them closer together considering the distance as measured around the pitch circumferential line of the teeth. This adjustment is so made that the next tooth is given a very slight cut and by reason of the novel arrangement of the operating elements of the machine the operator is 35 easily and quickly able to make the proper adjustment. The slight cut is then taken from all the teeth except the teeth which have been given the heavy cut since the faces of these teeth will have in effect retreated and will pass free of the 40 grinding wheel.

40 When the grinding wheel no longer cuts material from the teeth the wheel and finger are again adjusted so that another slight cut is taken.

45 This operation is repeated until the faces of the initially cut teeth begin to approach the grinding element. The operator at all times has the teeth under observation and as the wheel and finger begin to reach an adjustment which will bring them a distance apart which is nearing a space equal to a given number of equal parts of the pitch circumference of the cutter, the operator by exercising reasonable care can find this distance which becomes accurate as the initially 50 ground teeth begin to have material removed by the grinding wheel.

50 During the main grinding operation the space between the grinding wheel and the initially ground teeth is plainly visible to the operator and serves to indicate the approach of the necessary determined spacing between the grinding wheel

and finger which space must be equal to three tenths of the pitch circumference for a ten tooth cutter when the wheel and finger are initially spaced apart a distance equal to three teeth.

55 The initial spacing of three teeth is approximately three tenths but owing to the variations which may occur between the several teeth the initial spacing is obviously not accurate.

60 When practicing the above method the faces of the teeth are so ground that they are spaced apart exactly one tenth of the circumference or a distance equal to one or more equal parts of the circumference depending upon how many teeth happen to be in the cutter subjected to the grinding operation and according to the number of teeth the wheel is spaced from the finger.

65 When the faces 62" have been equalized the gashing wheel 63' may be operated to cut the slots 64 to the proper depth or the slots may be cut to the proper depth during the equalizing operation.

70 A roughing wheel 65 as shown in Fig. 6 is then used to rough out the teeth taking off a portion, leaving teeth 66 to be finished.

75 A finishing wheel 67 as shown in Fig. 7 is then used. This wheel has a curved surface and finishes teeth as indicated at 68.

80 It will be evident that since the first operation equalizes the spaces the roughing and finishing operations may be performed with very little attention on the part of the operator. The resultant teeth will be of equal width as well as accurately spaced since the operation of equalizing the teeth merely shifts the position of the teeth about the axis of the cutter. The actual positions of the teeth change, but their spacing and width are held uniform.

85 It may happen that a cutter may be received on which one or more teeth are out of spaced relation to an excessive degree and in practice therefor it may be desirable to first check for such abnormal variations. When the cutter is mounted on the arbor and the finger engages a tooth the grinding wheel may be moved so that it is in close relation to the face of a tooth. By reason of the present arrangement of parts in the machine the operator is able to quickly and conveniently observe the degree of space between the wheel and the surface to be ground.

90 With the wheel in close proximity to the surface of one tooth the operator proceeds to bring the teeth progressively to position adjacent to the wheel. As each tooth is positioned a variation in the space between wheel and tooth face will be apparent since as above set forth the operator is so positioned as to have a line of sight along the teeth and he may make an adjustment bringing the wheel and faces in such relation as to take off the high spots or to trim the faces of the teeth as a preliminary step in practicing the present method. The variations in the teeth may be very small and the trimming operation may not be necessary. It will be evident, however, that ordinarily with the usual method of grinding, slight inaccuracies would be built up whereas 95 with the present method they are corrected.

95 Although the above description includes the use of the gashing wheel to perform the equalizing operation it is evident that the roughing wheel or the finishing wheel may be used for this purpose. In practice, however, it has been found preferable to equalize the spacing of the teeth when cutting the slots or gashing.

100 With the above description in mind the importance of the present invention will be evident 105

and it will be appreciated that by reason of the present arrangement of the parts, their adjustability and the ease with which they may be controlled it is possible for an unskilled operator to produce a precision product at relatively high speed.

The present mechanism makes it possible for an operator to perform grinding operations on extremely hard material such as high speed steel with substantially the same ease and accuracy as would attend the cutting of soft or annealed metal.

Although a preferred embodiment of the invention is shown and described herein, it is to be understood that modifications may be made therein without departing from the spirit and scope of the invention as set forth in the appended claims.

What is claimed is:

1. A machine for grinding the faces of cutter teeth comprising a rotatable grinding wheel, an arbor, a holder for supporting said arbor beneath said wheel, means for slidably mounting a cutter on said arbor, a hand piece for moving said cutter on the arbor, means for adjusting said arbor to position said cutter for a tooth grinding operation

when said cutter is moved by means of said hand piece.

2. A machine for grinding the faces of cutter teeth comprising a rotatable grinding wheel, an arbor, a holder for supporting said arbor beneath said wheel, means for slidably mounting a cutter on said arbor, a hand piece for moving said cutter on the arbor, means for adjusting said arbor to position said cutter for a tooth grinding operation when said cutter is moved by means of said hand piece and means mounted on said holder for engaging a tooth of said wheel during a grinding operation.

3. A machine for grinding the faces of cutter teeth comprising a rotatable grinding wheel, an arbor, a holder for supporting said arbor beneath said wheel, means for slidably mounting a cutter on said arbor, a hand piece for moving said cutter on the arbor, means for adjusting said arbor to position said cutter for a tooth grinding operation when said cutter is moved by means of said hand piece and means mounted on said holder for engaging a tooth of said wheel during a grinding operation and means for adjusting said holder relative to said wheel.
